UNITED STATES PATENT OFFICE.

THOMAS H. THOMAS, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA.

ENGINEER'S BRAKE VALVE.

Application filed January 19, 1921. Serial No. 438,468.

To all whom it may concern:

Be it known that I, THOMAS H. THOMAS, a citizen of the United States, residing at Edgewood, in the county of Allegheny and 5 State of Pennsylvania, have invented new and useful Improvements in Engineers' Brake Valves, of which the following is a specification.

This invention relates to fluid pressure 10 brakes, and more particularly to the control of the main reservoir pressure.

With the present standard fluid pressure brake equipment there is usually provided what is termed a duplex pressure control 15 device having a maximum pressure head and an excess pressure head for governing the operation of the steam pump which compresses fluid into the main reservoir.

The maximum pressure head is adjusted 20 for a high main reservoir pressure such as 130 pounds, for example, and the excess pressure head for a lower main reservoir pressure, such as 90 pounds.

As heretofore operated, the excess pressure 25 head governs the main reservoir pressure in the full release position of the engineer's brake valve, so that the main reservoir pressure is limited to the lower maximum pressure of 90 pounds.

This has been found undesirable in some cases, for example, when trains are being moved down long steep grades, the frequent 30 applications and releases of the brakes consume so much air that eventually the main reservoir pressure may not be high enough 35 to permit the recharge of the brake pipe to the desired standard pressure.

The principal object of my invention is to provide for cutting out the excess pressure 40 head in the full release position of the brake valve, so that in this position, the main reservoir pressure is governed by the maximum pressure head and is therefore maintained at a higher maximum pressure.

In the accompanying drawing, the single 45 figure is a diagrammatic view, partly in section, of a portion of a locomotive brake equipment, illustrating the application of my improvement.

In the drawing, the duplex pressure controlling device or steam pump governor may 50 comprise a maximum pressure head 1, an excess pressure head 2, and a steam controlling valve device 3.

The steam controlling valve device 3 may 55 comprise a casing containing a valve 4 for controlling the supply of steam to the steam pump which compresses air into the usual main reservoir 5.

The valve 4 is operated by a piston 6, 60 subject on one side to the pressure of a spring 7 and having the opposite side open to a passage 8.

The maximum pressure head 1 may comprise a casing containing a diaphragm 9, 65 subject on one side to the pressure of an adjustable spring 10 and on the opposite side to fluid at main reservoir pressure supported through pipe 11. The diaphragm 9 controls a valve 12 for supplying fluid 70 under pressure to passage 8 and piston 6.

The excess pressure head 2 may comprise a casing containing a diaphragm 13, subject on one side to the pressure of an adjustable spring 14 and on the opposite side to fluid 75 under pressure supplied through pipe 15. The diaphragm 13 controls a valve 16 for also supplying fluid under pressure to passage 8 and piston 6.

The engineer's brake valve 17 may be of 80 the usual construction comprising a casing having a valve chamber 18, containing a rotary slide valve 19, adapted to be operated by a handle 20.

A pipe and passage 21 leads from the 85 usual feed valve device 22 to the seat of the rotary valve 19, and a main reservoir pipe 23 supplies fluid under pressure from the main reservoir 5 to the rotary valve chamber 18, the usual brake pipe 24 being connected to a passage 25, also leading to the seat of the rotary valve 19.

A pipe 26 connects the feed valve pipe 21 with the spring chamber 27 of the excess pressure head 2 and in full release position 95 of the brake valve, as shown in the drawing and according to my invention, the pipe 21 is connected by a port 28 through the rotary valve 19 with the rotary valve chamber 18. In full release position, the pipe 15 is also 100 connected to the rotary valve chamber 18 through a port 29.

It will now be clear, that in the full release position of the engineer's brake valve, as shown in the drawing, since fluid at main 105 reservoir pressure is supplied from the rotary valve chamber 18 through pipe 26 to the chamber 27, the fluid pressures on op-

posite sides of the diaphragm 13 will be equal, so that the spring 14 will operate on the diaphragm 13 to hold the valve 16 closed.

5 The excess pressure head 2 will therefore be cut out of action and the main reservoir pressure will be controlled by the maximum pressure head 1, which then operates the steam governor so as to maintain a higher 10 main reservoir pressure than is the case when the excess pressure head controls.

The main reservoir pressure having a higher maximum, the brake pipe pressure may be readily maintained at the desired 15 standard under such conditions as hereinbefore stated.

Having now described my invention, what I claim as new and desire to secure by Letters Patent, is:—

20 1. The combination with a main reservoir and a brake valve device having the usual full release position, of a duplex pressure governor having a pressure head for limiting the maximum pressure in the main reservoir to a predetermined high degree and a pressure head for limiting the maximum pressure in the main reservoir to a predetermined lower degree, and means operative in 25 full release position of the brake valve de-

vice for cutting the low pressure head out of 30 action.

2. The combination with a brake valve and a main reservoir, of a duplex pressure governor having a low pressure head for 35 limiting the main reservoir pressure to a predetermined maximum degree and a high pressure head for limiting the main reservoir pressure to a higher predetermined maximum degree and means for preventing the operation of the low pressure head in 40 the full release position of the brake valve.

3. The combination with a brake valve and a main reservoir, of a duplex pressure governor having a low pressure head including a diaphragm subject to the opposing pressures of an adjustable spring and main reservoir pressure for limiting the main reservoir pressure to a predetermined maximum and a high pressure head for limiting the main reservoir pressure to a higher 50 maximum degree and means for supplying fluid at main reservoir pressure to the spring side of said diaphragm in the full release position of the brake valve.

In testimony whereof I have hereunto set 55 my hand.

THOMAS H. THOMAS.
